UNITED STATES PATENT OFFICE.

MARTINUS FLUTO, OF WYNDMERE, NORTH DAKOTA.

ROAD GRADER.

Application filed November 6, 1924. Serial No. 748,233.

To all whom it may concern:

Be it known that I, MARTINUS FLUTO, a citizen of the United States, residing at Wyndmere, in the county of Richland and State of North Dakota, have invented certain new and useful Improvements in Road Graders, of which the following is a specification, reference being had to the accompanying drawings.

10 This invention relates to improvements in road graders, and more particularly to push road graders employed in the construction of crown roads.

It is well known to those familiar with the use of these machines in this type of work that during the first cut, which is made at the extreme side of the road and serves to form a vertical angular wall forming the junction of the edge of the road with the side and providing a ditch, there is no tendency of the scraper toward sidewise movement, the end of the scraper blade being against the formed side wall. When, however, grading cuts are made, in which 25 the edge of the scraper is spaced from the ditch and side wall, there is a tendency of the grader, due to the heavy weight of material which is being shifted transversely of the road by the angular scraper blade, to move toward this side wall of a sidewise skidding movement which renders control of the scraper extremely difficult and often results in damage thereto.

An important object of this invention is 30 to provide a simple attachment for these road graders whereby they may be supported in spaced relation to this side wall during such grading cuts after the first cut.

A further object of the invention is to 35 produce a device of this character which may be readily attached to road graders now in use without in any manner altering the present construction thereof and without in any manner interfering with the operation thereof.

A still further object of the invention is to 40 provide a device of this character which will be durable and efficient in service, which is readily repaired and moved to operative and inoperative position, and which is generally facile in its manipulation.

These and other objects I attain by the construction shown in the accompanying

drawings, wherein for the purpose of illustration is shown a preferred embodiment of my invention and wherein:—

Figure 1 is a plan view of a road grader having an attachment constructed in accordance with my invention;

Figure 2 is a perspective of the various parts of the hinge and extensible bar;

Figure 3 is a perspective of the yoke and flexible connection employed for connecting the yoke with the forward end of a longitudinally extending frame member of the road grader;

Figure 4 is a sectional view showing in dotted lines the approximate position assumed by the caster-wheel during operation of the road grader.

Referring now more particularly to the drawings, the numeral 10 indicates the longitudinally extending body frame members of a road scraper of any desired character, these frame members being supported at the front and rear of the machine by wheels 11 mounted upon transversely extending supporting axles 12. 13 designates the transversely extending scraper blade which is inclined from one side to the other of the machine so that earth removed thereby is shifted to one side of the machine and discharged. The above structure is all old and well known and is in no way claimed by me as a part of my invention except in combination with the structure hereinafter described.

In accordance with my invention, I provide means for securing to the rear end of the longitudinally extending frame member 10, at that side of the machine opposite from that at which the earth is discharged, one section 14 of a universal hinge, the opposite section 15 of which is carried by an extensible bar 16, the opposite end of which has mounted therein a fork 17 in which is disposed a caster-wheel 18.

The arms 19 of the fork are engaged by the ends of a U-shaped clevis yoke 20, the bight portion 21 of which has a plurality of transversely spaced openings 22 for the reception of a pivot bolt 23 forming a means for attaching a cable eye 24. To this cable eye 24 is attached one end of a cable 25, the forward end of which has attached thereto one end of a length of

chain 26, the opposite end of which is provided with a hook 27 which, after the chain has been engaged about the longitudinally extending frame member 10 adjacent the forward end of the grader, may be engaged with the links of the chain to hold the same in adjusted position.

The frame member attached section 14 of the hinge preferably consists of a ball, of a ball and socket joint, the section 15 being formed as a socket and in two parts 28 and 29 adapted to be assembled upon the ball. The ball 14 is formed upon one end of a bar 30 having formed therein adjacent one end an opening 31 and adjacent the opposite end a longitudinally extending slot 32. A clamping plate 33 is associated with the bar having openings corresponding to the opening 31 and slot 32, securing elements 20 being directed through these openings and adapted to be arranged upon the upper and lower sides of the frame member 10. The slots formed in the bar and plate permit adjustment of the securing elements toward 25 and away from one another to accommodate frame members of varying widths. The extensible bar 16 is preferably in the form of two telescopically engaged sections of pipe 34 and 35 having longitudinally 30 spaced openings therethrough adapted for interchangeable reception of a securing element whereby the effective length of the bar may be varied to suit the needs of a particular machine and a particular spacing 35 of the cut from the side of the road.

In the use of the device the bar acts as a positive limit to determine the distance toward the side bank B through which the grader may move, the cable connection with 40 the forward end of the machine serving to limit the rearward movement of the bar. The universal hinge will permit movement of the outer end of the bar sufficiently to accommodate various roughnesses which are 45 always met with in road construction, and particularly at the point at which the caster-wheel will operate, this being at the junction of the wall B with the road surface R. During the first cut and at other times when not 50 needed, as during transportation of the grader from place to place, the bar may be swung to a position where it parallels the frame member 10 to which it is attached and secured in such position by its cable connection.

Since obviously the structure hereinbefore set forth is capable of a certain range of change and modification without materially departing from the spirit of my invention, I 60 do not limit myself to such specific structure except as hereinafter claimed.

I claim:

1. In combination with a road grader having a longitudinally extending frame mem-

ber, an extensible bar pivoted to said frame member and swingable from a position where it parallels the frame member to a position where it extends outwardly, downwardly and slightly rearwardly from the frame member, said rod being of greater length than the vertical distance between its pivot and the ground, a caster-wheel carried by the outer end of the bar, and a flexible connection between the caster-wheel and said longitudinally extending frame member at a point in advance of such pivotal connection.

2. In combination with a road grader, a bar pivotally secured to the road grader and swingable about the pivot thereof from a position where it extends longitudinally of the road grader to a position where it extends outwardly, downwardly and rearwardly from the road grader, and a flexible connection between the outer end of the bar and the road grader in advance of such pivotal connection, the outer end of said bar being provided with a ground-engaging wheel, said rod being of greater length than the vertical distance between its pivot and the ground.

3. In combination with a road grader, a member attachable to the road grader adjacent the rear end thereof and including one member of a universal hinge, a bar formed in two telescopically engaged sections having means whereby they may be held in adjusted positions, one of said sections being provided with the other member of the universal hinge, the other of the sections being provided with a ground-engaging wheel, and a flexible element engaged with the outer end of the last named section and adapted for connection with the road grader at a point in advance of the point of attachment of the first named member, said bar sections when telescoped to their fullest extent being of greater length than the vertical distance between the ground and the point of attachment of the first named member.

4. In combination with a road grader, a member attached to the road grader adjacent the rear end thereof and including one member of a universal hinge, a bar formed of two telescopically engaged sections each having a series of openings, a securing element selectively engageable in the opening of the sections to thereby maintain the bar in a desired adjusted length, one of said sections being provided with the other member of the universal hinge, the other of the sections being provided with a ground-engaging wheel, and a connection between the bar and the grader limiting rearward movement of the free end of the bar with relation to the grader, said bar sections when telescoped to their fullest extent being of greater length

than the vertical distance between the ground and the point of attachment of the first named member.

5. In combination with a road grader, a member attachable to the road grader adjacent the rear end thereof and including one member of a universal hinge, a bar formed in two telescopically engaged sections having means whereby they may be held in adjusted positions, one of said sections being provided with the other member of the universal hinge, the other of the sections being provided with a ground-engaging wheel, and a flexible element engaged with the outer

end of the last named section and adapted 15 for connection with the road grader at a point in advance of the point of attachment of the first named member, said hinge permitting shifting of the bar to a point where it extends longitudinally of the grader, said 20 bar sections when telescoped to their fullest extent being of greater length than the vertical distance between the ground and the point of attachment of the first named member.

In testimony whereof I hereunto affix my signature.

MARTINUS FLUTO.
